[57] **CLAIM**

The ornamental design for a folding room divider, as shown and described.

DESCRIPTION

FIG. 1 is a front perspective view of a folding room divider showing our new design;

FIG. 2 is a top plan view thereof;

FIG. 3 is a side elevational view the opposite side being identical thereto;

FIG. 4 is a front elevational view, the rear view being a mirror image thereof;

FIG. 5 is a bottom plan view thereof; and

FIG. 6 is a top plan view of the folding room divider, in partially folded condition.

FIG. 1

FIG. 3

FIG. 2

FIG. 4

FIG. 5

FIG. 6
